UNITED STATES PATENT OFFICE.

SAMUEL KOHN, OF NEW YORK, N. Y., ASSIGNOR TO MERGENTHALER LINOTYPE COMPANY, A CORPORATION OF NEW YORK.

ESCAPEMENT MECHANISM FOR TYPOGRAPHICAL MACHINES.

Application filed January 28, 1927. Serial No. 164,189.

This invention relates to escapement devices such as are employed in commercial linotype machines to control the release of matrices from their storage magazine. Ordinarily, the escapement devices comprise, for each magazine channel or matrix column, a centrally pivoted rocking lever and a pair of matrix engaging pawls or verges attached to the opposite ends thereof, these pawls being projected alternately into the magazine through suitable openings cut through one of its side plates. The escapements as thus constituted are usually actuated by a series of vertical reeds operated by pivoted yokes or levers each containing a rotary cam or eccentric which is adapted to make peripheral contact with an underlying constantly rotating rubber-covered roll. The pivoted yokes are held normally with their cams at rest and out of contact with the rubber-covered roll and are released by the manipulation of finger keys which permit the cams to fall into engagement with the driving roll and be rotated thereby to raise the yokes and operate the escapements.

The object of the present invention is to simplify the foregoing arrangement and to obviate many of the objections attending the use of such arrangement. To this end, it is proposed to make the escapement devices in the form of rotatable cams which are mounted beyond the delivery end of the magazines and are adapted by their rotation to release the matrices, one at a time, into the fixed assembler throat. These escapement cams are loosely mounted on a metal driving roll and are capable of being individually coupled thereto by key-controlled clutch members which are pivoted to the cams and are provided with teeth arranged to engage one or another of several longitudinal grooves formed in the driving roll.

In the accompanying drawings, the invention has been shown merely in preferred form and by way of example and as applied to a linotype machine, but obviously many changes and variations may be made therein and in its mode of application which will still be comprised within its scope. For instance, it is equally applicable to machines which handle type or type dies instead of intaglio matrices, and the reference hereinafter to matrices is intended to include such male or cameo typographical elements. It should therefore be understood that the invention is

not limited to any specific form or embodiment except in so far as such limitations are specified in the claims.

In the drawings:

Fig. 1 is a vertical section taken through the lower end of a linotype magazine and the associated assembler throat, showing the application of the improved escapement device;

Fig. 2 is a similar view showing the device in the act of releasing a matrix;

Fig. 3 is a section taken on line 3—3 of Fig. 1; and

Fig. 4 is a detail perspective view of one of the escapement units.

As shown in Fig. 1, the matrices X are stored in two or more superposed channeled magazines A which are shiftable upwardly and downwardly in the machine frame so that the selected one may be brought into operative relation to the fixed assembler throat B. Normally, the matrices are locked in their respective magazines by the usual locking rod A¹ but when a font is selected for use, the rod is withdrawn or otherwise rendered inactive so that the matrices may be allowed to escape from the magazine under the control of escapement devices which release them, one at a time, and allow them to pass by gravity into throat B for composition in line at a lower level.

The improved escapement devices which constitute the subject matter of the present invention comprise a series of rotatable cams C located beyond the lower or delivery end of the magazine and mounted on a constantly driven metal roll C¹, the latter being journaled at its opposite ends in bearing arms C² pivoted to the fixed framework and which permit the escapements to be rocked forwardly out of the way of the magazines as the latter are interchanged in operative position with each other. A pull spring C³ connected to one of the bearing arms C² and a stop screw C⁴ banking against the back plate of the throat B serve to maintain and locate the escapement cams in operative relation to the magazine being used. The cams C correspond in number to the magazine channels and are arranged to engage and support the contained matrix columns, each cam being formed with a pair of oppositely disposed high concentric portions C⁵, one of which normally engages the lower edge of the leading matrix of the corresponding column. The individual cams are further

formed with a pair of low non-concentric portions C^6 alternating with the high portions C^5 and which permit the matrices to slide forwardly from the magazine in the 5 rotation of the cams, as well as with a pair of shoulders C^7 intermediate of the respective pairs of high and low portions and adapted to engage the matrices, and support them momentarily during their passage 10 from the magazine into the assembler throat B (see broken line Fig. 1). The peculiar form of the cams and the opposed relation of the shoulders C^7 provide for the release of a matrix at every half-revolution of the 15 cams.

The escapement cams C are loosely mounted on the driving roll C^1 but are capable of being individually connected thereto by means of clutch pawls C^9 pivoted at c to the 20 sides of the cams. Flanges or hubs C^{10} formed on the cams serve to maintain them in spaced relation on the roll C^1 and the widths thereof vary according to the spacing of the magazine channels. The pawls 25 C^9 are each formed with a tooth c^1 projecting inwardly therefrom and arranged to engage one or another of several grooves c^2 formed in the driving roll C^1 and extending throughout the length thereof. Plate 30 springs C^{11} , anchored to the cams and pressed against one end of the attached pawls, tend constantly to move the teeth into engagement with the grooves c^2 , it being noted that the hubs C^{10} are notched or cut 35 away to permit passage of the teeth therethrough. In order to hold the pawls normally disengaged from the driving roll against the tension of the springs C^{11} , they are formed with diametrically opposite 40 banking surfaces c^3 c^4 , one or the other of which is adapted to engage the free ends of pivoted trip levers D at every half-revolution of the cams C. These trip levers are 45 connected at their opposite ends to a series of vertical reeds E slidably mounted in the machine and which, in the present instance, are connected directly to the finger keys F of the keyboard.

According to the foregoing arrangement, 50 the depression of a finger key F rocks the associated lever D through the intervening reed E and trips the clutch pawl C^9 of the corresponding escapement cam C, permitting the tooth c^1 of said pawl to be pressed by the spring C^{11} into driving engagement with one of the grooves c^2 of the driving roll C and thus causing rotation of the cam in the direction indicated by the arrow in Fig. 1. As the active concentric portion C^5 55 passes out of engagement with the leading matrix of the column, the adjoining reduced portion C^6 comes into play and allows the matrix to slide forwardly against the intermediate shoulder C^7 and, as the cam continues to rotate, the matrix is supported by 60

said shoulder until it has passed completely out of the magazine upon the reduced portion C^6 of the cam (see Fig. 2). At this moment, as will be noted, the upper end of the escaping matrix is lifted slightly by the 70 cam and the other concentric portion C^5 passes beneath the lower end of the next or succeeding matrix of the column. A slight further rotation of the cam disengages the shoulder C^7 from the escaping matrix and 75 releases it entirely, the second concentric portion holding back the next matrix. In the meantime, due to the release of the finger key, the trip lever D will have resumed its normal position so that, when the cam has 80 about completed a half-rotation in effecting the release of the matrix, the banking surface c^3 or c^4 , as the case may be, of the clutch pawl engages the free end of said lever and forces the tooth c^1 out of engagement with 85 the driving roll C^1 , allowing the cam to come to rest. Upon the next actuation of the finger key, the other pair of high and lower surfaces of the cam with its intermediate shoulder will function in a similar fashion 90 to effect the release of the next and now the leading matrix.

The speed at which the roll C^1 is driven may be determined by the time it ordinarily takes a matrix of average thickness to pass 95 from its position of rest within the magazine to its releasing position. Otherwise, e. g., if the roll were driven at too great a speed, the reduced portions C^6 of the cams might engage escaping matrices before they 100 had time to leave the magazine and bind them against the upper plate thereof.

Many advantages characterize the improved construction. As will be apparent, the mechanism is self-contained, easily assembled, and inexpensive to manufacture, as well as positive and reliable in operation. Moreover, a single bank or row of the escapement units, due to their independent mounting, will suffice to control the release 105 of matrices from any desired number of magazines, and this without changing the general structure or organization of the machine. Since the escapements are located beyond the magazines, the latter may be 110 brought much closer together than ordinarily. The magazines themselves are simpler and may be produced more cheaply than those now in use, the bottom plates being unapertured and solid throughout. The improved escapement is not only well 115 adapted to cooperate with the standard matrix without change, but it is also capable of functioning equally well with earless matrices or matrices of plain rectangular form. These and other advantages will be 120 readily appreciated by those skilled in the art.

As previously stated, many changes and 125 variations in the construction and operation 130

of the improved device may be made and still be comprised within the spirit of the invention. For example, while the connection and disconnection of the escapement cams with and from the driving roll as above described is effected by means of clutch pawls, it is obvious that such connection could be established in various other ways. Again, the release of the individual matrices could be accomplished in a way similar to that disclosed if the escapement cams were formed with a greater or less number of high and low surfaces with their intermediate shoulders. The invention is therefore not limited to any specific form or embodiment except in so far as such limitations are specified in the appended claims.

Having thus described my invention, what I claim is as follows:

1. In a typographical machine, the combination of a magazine adapted to contain a column of matrices, a rotary escapement arranged to cooperate with the matrices and control their release, one at a time, from the magazine, a driving element for the escapement, and means whereby the escapement may be connected with and disconnected from the driving element as required.

2. In a typographical machine, the combination of a magazine adapted to contain a column of matrices, a rotary escapement arranged to cooperate with the matrices and control their release, one at a time, from the magazine, a rotary driving element upon which the escapement is loosely mounted, and means for connecting and disconnecting the escapement with and from the driving element as required.

3. In a typographical machine, the combination of a magazine adapted to contain a column of matrices, a rotary escapement arranged to cooperate with the matrices and control their release, one at a time, from the magazine, a rotary driving element normally disconnected therefrom, a clutch for establishing a driving engagement between said elements, and means for engaging and disengaging the clutch as required.

4. In a typographical machine, the combination of a magazine adapted to contain a column of matrices, a rotary escapement arranged to cooperate with the matrices and control their release, one at a time, from the magazine, a rotary grooved driving element upon which the escapement is loosely mounted, a clutch pawl carried by the escapement, and controlling means whereby the clutch pawl may be engaged with and disengaged from the grooved driving element as required.

5. In a typographical machine, the combination of a matrix magazine, a rotary escapement mounted independently of the magazine and adapted by its rotation to control the release of the matrices therefrom,

and key-controlled power-actuated means for imparting the rotary movement to the escapement.

6. In a typographical machine, the combination of a magazine adapted to contain a series of matrix columns, a power-driven roll mounted independently of the magazine, a series of rotary escapements loosely mounted on the roll and arranged to cooperate directly with the respective matrix columns in the magazine, means for establishing a driving connection between the escapements and the power-driven roll, and means for controlling the connection and disconnection of the escapements individually with and from the power-driven roll.

7. In a typographical machine, the combination of a magazine adapted to contain a series of matrix columns, a power-driven roll, a series of rotary escapements loosely mounted thereon and arranged to cooperate directly with the respective matrix columns in the magazine, clutch pawls carried by the respective escapements for establishing a driving connection between them and said roll, and controlling means whereby the clutch pawls may be individually engaged with and disengaged from the power-driven roll as required.

8. In a typographical machine, the combination of a matrix magazine, an assembler throat communicating with the delivery end thereof, and an intermediate rotatable escapement formed to engage the lower edges of the individual matrices as the escapement is rotated and to support them momentarily as they pass from the magazine into the assembler throat, for the purpose described.

9. In a typographical machine, the combination of a matrix magazine, and a rotary escapement associated therewith but mounted independently thereof, said escapement being adapted by its rotation to control the release of the matrices from the magazine.

10. In a typographical machine, the combination of a matrix magazine, and a rotary escapement associated therewith but mounted independently thereof, said escapement being arranged to cooperate with the matrices and operable in successive half-revolutions to control their release, one at a time, from the magazine.

11. In a typographical machine, the combination of a matrix magazine, an assembler throat, and an intermediate rotary escapement associated with the magazine and adapted by its rotation to control the release of the matrices therefrom, said escapement serving to conduct the matrices into the assembler throat as they are released from the magazine.

12. In a typographical machine, the combination of a magazine adapted to contain a column of matrices, and a rotary escapement to control the release of the matrices,

one at a time, from the inagazine, said escapement being disposed beyond the delivery end of the magazine and formed to give temporary support to the individual matrices in their passage from the magazine.

13. In a typographical machine, the combination of a magazine adapted to contain a column of matrices, and a rotary escapement to control the release of the matrices, one at a time, from the magazine, said escapement being disposed beyond the delivery end of the magazine and formed to lift the individual matrices at their upper ends after they have passed clear of the magazine.

14. In a typographical machine, the combination of a magazine adapted to contain a column of matrices, and a rotary escapement disposed beyond the delivery end of the magazine and actuatable to control the release of the matrices, one at a time, from the magazine.

15. In a typographical machine, the combination of a magazine adapted to contain a column of matrices, and a rotary escapement disposed beyond the delivery end of the magazine and rotatable in the direction of travel of the matrices to release them, one at a time, from the magazine, said escapement presenting alternate low and high portions and an intermediate connecting shoulder, as and for the purpose described.

16. In a typographical machine, the combination of a magazine adapted to contain a column of matrices, and a rotary escapement disposed beyond the delivery end of the magazine and rotatable in the direction of travel of the matrices to release them, one at a time, from the magazine, said escapement presenting a high concentric portion, a low non-concentric portion, and a shoulder intermediate of the two said portions.

17. In a typographical machine, the combination of a magazine adapted to contain a column of matrices, and a rotary escapement disposed beyond the delivery end of

the magazine and rotatable in the direction of travel of the matrices to release them, one at a time, from the magazine, said escapement presenting a high concentric portion 50 adapted to engage the lower end of the leading matrix and hold it within the magazine, a low non-concentric portion adapted in the rotation of the escapement to permit the leading matrix to slide forwardly from the 55 magazine, and a shoulder intermediate of the two said portions and serving to retain the leading matrix against escape until the high concentric portion of the escapement is brought into engagement with the lower end 60 of the next succeeding matrix.

18. In a typographical machine, the combination of a magazine adapted to contain a column of matrices, and a rotary escapement disposed beyond the delivery end of the 65 magazine and rotatable in the direction of travel of the matrices to release them, one at a time, from the magazine, said escapement comprising a plurality of high concentric portions adapted successively to engage 70 the lower ends of the leading matrices and hold them back within the magazine, and a corresponding plurality of non-concentric portions adapted in the rotation of the escapement to permit successive leading matrices to slide forwardly from the magazine, and a shoulder intermediate of the high and low portions of each pair and serving to retain the leading matrix against escape until the high-concentric portion of the escapement is brought into engagement with the lower end of the next succeeding matrix. 75

19. In and for a typographical machine, a matrix releasing escapement comprising the rotary cam C formed with the two high 80 concentric portions C⁵ and the two low non-concentric portions C⁶ together with the intermediate shoulders C⁷, said parts operating substantially as shown and described.

In testimony whereof, I have affixed my 85 signature hereto.

SAMUEL KOHN.
